RIDING MOWER

Robert B. Mead, Wilmington, Ohio, assignor to Mast-Foos Manufacturing Company, Inc., Springfield, Ohio

Filed May 27, 1970, Ser. No. 23,170

Term of patent 14 years

Int. Cl. D15—03

U.S. Cl. D40—1

FIG-1

FIG-2

FIG-3

FIG-4

FIG-5

FIG-6

FIG. 1 is an elevation view of one side of a riding mower showing my new design;

FIG. 2 is a front end view;

FIG. 3 is an elevation view of the opposite side of the riding mower;

FIG. 4 is a rear elevation view;

FIG. 5 is a top plan view, in plan; and

FIG. 6 is a perspective view of a modified embodiment of the riding mower illustrated in FIG. 1.

I claim:

The ornamental design for riding mower, substantially as shown and described.
